FINISHING MACHINE FOR CONCRETE SURFACES
Ralph G. Barnes, Vandalia, Ohio
(4361 Wallington Drive, Dayton 40, Ohio)
Filed Sept. 12, 1958, Ser. No. 755,180
5 Claims. (Cl. 94—45)

This invention relates to a finishing machine for concrete surfaces and more particularly to a machine for finishing the surface of freshly laid concrete paving, however, the invention is not necessarily so limited.

In laying concrete paving, a screed or strike-off bar is employed to doctor the freshly laid concrete surface to the desired elevation or thickness. In conventional practice, the screed is mounted on a mobile apparatus and drawn along the freshly laid pavement immediately as it is laid. Often, to facilitate the operation of the screed it is oscillated in the direction of its length as it is drawn over the freshly laid pavement.

In addition to the use of screeds or strike-off bars for doctoring the surface of the freshly laid pavement, it has become conventional practice to vibrate the freshly laid concrete. The vibration yields two important results. One is that the concrete material is compacted to eliminate any voids in the concrete body. The other is that a layer of grout is brought to the surface of the pavement to enable final finishing as desired.

A vibratory screed capable of doctoring the freshly laid pavement to the desired thickness and also having the desired vibratory characteristics for compacting the pavement is disclosed in my United States Letters Patent No. 2,542,979 issued February 27, 1951, and entitled "Screeds for Cement Surfaces." Screeds of the type disclosed in the aforementioned patent have vastly simplified the apparatus required for finishing concrete pavement. A limitation common to this type of equipment, however, is that it cannot easily be adjusted to finish road beds of varying width and varying crown. Equipment which can be adjusted to vary road width and crown tends to be quite massive and for this reason is unacceptable in many applications, such as bridge deck finishing.

An object of this invention is to provide a finishing machine for concrete surfaces which is sufficiently light in weight that it may be used for finishing bridge decks and the like.

Another object of this invention is to provide in a finishing machine for concrete surfaces an improved vibratory element for compacting the concrete surface.

Another object of this invention is to provide an improved strike-off bar for use in planing or troweling the surface of freshly laid concrete pavement.

Still another object of this invention is the provision of an improved finishing machine for concrete surfaces including a strike-off bar which is adjustable to provide a curvature therein so as to establish a crown in the concrete surface being finished.

A further object of this invention is the provision of an improved machine for finishing concrete surfaces including vibratory elements for vibrating and thereby compacting the concrete body, said machine further including means for adjusting the position of said vibratory elements to accommodate a crown in the concrete surface which is being finished.

Yet another object of this invention is the provision of a finishing machine for concrete surfaces including a strike-off bar for planing the surface to the desired thickness and one or more vibratory members for compacting the surface which is to be finished.

Still a further object of this invention is the provision of a machine for finishing concrete surfaces including a

2

strike-off bar which may be adjusted to provide a crown in the concrete surface and vibrating elements for compacting the concrete surface after it has been doctored by the strike-off bar, the machine including means for adjusting said vibratory elements to accommodate the crown established by said strike-off bar.

Still a further object is to provide a new and improved method for finishing freshly laid concrete surfaces where in the surface is planed to provide a crown therein and vibrated so as to compact the concrete body without substantial destruction of the crown provided therein.

Other objects and advantages reside in the construction of parts, the combination thereof, the method of manufacture, and the mode of operation, as will become more apparent from the following description.

In the drawings, FIGURE 1 is a perspective view with parts removed to reveal interior detail illustrating the machine of this invention.

FIGURE 2 is a perspective view drawn to reduced scale illustrating an inner truss member employed in the framework of the machine of FIGURE 1.

FIGURE 3 is a perspective view illustrating schematically the structural assembly of the machine of FIGURE 1.

FIGURE 4 is a fragmentary end elevational view of the machine of FIGURE 1, with the supporting structure removed, illustrating schematically the operative elements of the machine.

FIGURE 5 is an elevational view illustrating schematically the arrangement of vibrator elements in the machine of FIGURE 1 for vibrating a pavement having a predetermined crown.

FIGURE 6 is an enlarged front elevational view taken in the direction of the line 6—6 of FIGURE 1.

FIGURE 7 is an end elevational view of the vibrator structure illustrated in FIGURE 6.

FIGURE 8 is an enlarged end elevational view taken in the direction of the line 8—8 of FIGURE 1.

FIGURE 9 is a front elevational view of the structure illustrated in FIGURE 8.

FIGURE 10 is an enlarged rear elevational view taken substantially in the direction of the line 10—10 of FIGURE 1.

Referring to the drawings in greater detail, the machine of this invention is illustrated in FIGURE 1. This machine is designed to move longitudinally along a highway bed behind an apparatus depositing fresh concrete to form the highway. To this end, rails 10 supported by suitable standards 12 are provided on both sides of the highway.

The concrete finishing machine is provided with wheels 14 for traveling upon the rails 10.

On each end of the machine the forward wheel 14, as viewed in FIGURE 1, is supported upon an axle 16 journaled in a lever arm 18. The lever arm 18 is pivoted on 55 a pin 20 to a bracket 22 welded to a transverse channel member 24. The arrangement is such that pivotal movement of the lever arm 18 will function to raise and lower the transverse channel member 24 relative to the forward wheel 14.

60 A rear wheel 14 on each end of the machine, as viewed in FIGURE 1, is supported upon an axle 26 journaled in a lever arm 28. The lever arm 28 is pivotally secured by means of a pivot pin 30 to a bracket 32 welded to the transverse channel member 24. Wheel scrapers 33 secured to the transverse channel member 24 engage the rims of the wheels 14.

The lever arms 18 associated with the front wheels 14 and the lever arms 28 associated with the rear wheels 14 are joined by a connecting link 34. The forward end of 70 the link 34 is provided with an elongate slot 36 so that the lever arm 18 is engaged with lost motion. The assembly of lever arms 18 and 28 together with the linkage 34 is

duplicated on each side of the wheels 14 at each end of the finishing machine. As clearly illustrated in FIGURE 1, the elongate lever arms 28 associated with the rear wheels 14 are joined by transverse rungs 29.

The arrangement is such that a pivoting movement of the rear lever arms 28 in the clockwise direction, as viewed in FIGURE 1, may be used to elevate the transverse channel member 24 relative to the highway bed, while pivotal movement of the rear lever arms 28 in the reverse direction will function to lower the transverse channel member 24. The lever arms 28 are shown in the extreme counterclockwise position at the right end of the machine in FIGURE 1 and in the extreme clockwise position at the left end of the machine in FIGURE 1.

As best illustrated at the right end of the machine of FIGURE 1, the forward wheel supporting bracket 22 is provided with a plurality of spaced holes 38 adapted to receive a lock pin 40. Similar holes and a lock pin 40 are provided on the opposite side of the bracket 22. The lock pins 40 determine the counterclockwise position of the lever arms 18. Thus, by rotating the lever assembly in the clockwise direction, then inserting the pins 40 in any of the holes 38, then returning the lever assembly to its counterclockwise position, the lock pins 40 may be used to support the lever arms 18 in a predetermined intermediate position such that the forward end of the channel member 24 is elevated. The lost motion slot 36 in the links 34 will permit full counterclockwise travel of the lever arms 28, however, such that the rear end of the channel member 24 will not be correspondingly elevated. Similar locking mechanism is provided on the left end of the machine.

The levers associated with the wheels 14 at each end of the finishing machine thus provide a means for elevating the channel members 24 as desired and for selectively retaining the forward ends of the channel members 24 at an elevated position.

The transverse channel members 24 at either end of the machine of FIGURE 1 support a telescoping truss assembly as described in the following. Secured in spaced relation to the channel member 24 at the right end of the machine of FIGURE 1 is a rectangular outer truss assembly 42 comprising parallel upright trusses 42a and 42b. The top portions of these trusses are supported in fixed spaced relation by transverse angle bars such as identified in the drawings by reference numerals 44a, 44b, and 44c. The bottom of the trusses 42a and 42b are connected in spaced relation by channel members such as illustrated at 46a and 46b in FIGURE 1.

The transverse channel member 24 at the left end of the machine of FIGURE 1 supports a similar outer truss assembly 48 comprising parallel upright trusses 48a and 48b. These trusses 48a and 48b are supported in fixed spaced relation at their tops by transverse angle bars such as designated by the reference numerals 50a, 50b, and 50c. At their bottoms, these trusses 48a and 48b are connected by transverse channel members such as illustrated at 52a and 52b in FIGURE 1.

The rectangular outer truss assemblies 42 and 48 provided at each end of the machine of FIGURE 1 telescopically receive a rectangular inner truss assembly 54 illustrated in FIGURE 2. This inner truss assembly has been omitted from the machine as illustrated in FIGURE 1 to avoid confusion of detail. With reference to FIGURE 2 the inner truss assembly 54 comprises parallel upright side trusses 56a and 56b secured in spaced relation by angle bars indicated by the reference numerals 58a, 58b, 58c and 58d at the top, and by end braces represented by the numerals 60a and 60b at the bottom. The angle bars which make up this inner truss assembly 54 each have their flanges turned inwardly so that this inner truss assembly will slide freely in the outer truss assemblies of FIGURE 1.

The telescoping arrangement of the truss assemblies is illustrated in FIGURE 3. There it will be observed

that the inner truss assembly 54 projects into the ends of the outer truss assemblies 42 and 48 much like the inner slide of a conventional match box. The arrangement is such that the length of the machine illustrated may be varied from a minimum represented by the combined lengths of the trusses 42 and 48 to a maximum represented by the combined lengths of the trusses 42 and 48 plus about four-fifths of the length of the truss assembly 54. At the maximum extension of the machine, the end portions of the truss assembly 54 must project into the ends of the assemblies 42 and 48 a sufficient distance to provide support for the outer truss assemblies 42 and 48. At any given extension the truss assemblies are all bolted together to make a rigid structure.

The primary operative elements of the machine of this invention are illustrated in FIGURE 4. This figure depicts schematically and in phantom detail the assembly of wheels 14 with the transverse channel member 24 at one end of the machine. The machine is positioned above a concrete deposit designated by the reference numeral 62. At the forward end of the machine a strike-off bar 64 is supported in contact with the concrete surface. This bar 64 is of a general L-shaped section and is provided with a scoop 66 at the forward end thereof for planing the surface of the concrete deposit 62.

To the rear of the strike-off bar 64 the machine supports a pair of like elongate vibratory beams 68a and 68b. Only one of the beams 68a is illustrated in FIGURE 4. This beam has a substantial L-shaped section and is provided with a trailing flange 70 adapted to slap the surface of the concrete deposit 62 thereby to compact the deposit.

The machine is adapted to be moved so as to pull the strike-off bar 64 in advance of the vibratory beam 68a along the concrete deposit as it is being formed, and to this end there is provided, at each end thereof, a hand winch 72 mounted upon a post 74. The posts 74 are secured at the ends of the machine to the forward ends of the channel members 24. The winch cable 76 is adapted for connection to any suitable stationary object forward of the machine so that the winches 72 may be operated manually to draw the finishing machine across the surface of the freshly laid concrete deposit at the desired speed. Where desired, powered winches may be substituted for the hand winches. The use of winches is found preferable to the provision of power directly at the wheels 14 for the reason that the weight of the machine is insufficient to provide adequate traction for these wheels.

The vibratory beams 68a and 68b and the supporting structure therefor will now be described in detail. With reference to FIGURE 1, both vibratory beams are illustrated. The construction of these beams is identical. As best illustrated in FIGURE 7, the vibratory beam 68a is formed of an elongate sheet folded to substantially an L-shaped section. Preferably, the vibratory beams are formed of a flexible sheet metal material which may be heavy gauge sheet steel, as an example.

With the metal sheet of the beam 68a folded to an L-shaped section, two flanges are identifiable. One of these is the flange 70, which is so positioned as to engage the concrete surface which is being finished in face to face contact. The other is a flange 80 which is oriented upright or normal to the surface of the concrete. The flanges 70 and 80 are joined by an arcuate portion or crease 82. The upper margin of the upright flange 80 is provided with a reinforcing rib 84 formed by a length of rigid pipe welded thereto.

The structure for securing the vibratory beam 68a to the finishing machine includes a clamp assembly 86 which is visible near the center of the finishing machine, as illustrated in FIGURE 1. This clamp assembly and the supporting structure associated therewith is best observed in FIGURES 6 and 7. As clearly illustrated in these figures, the clamp assembly 86 engages the reinforce-

ing rib 84 for the vibratory beam 68a. The gripping action of the clamp assembly is controlled by a hexagonal nut 88.

With reference particularly to FIGURE 6, a bracket 90 is bolted to the clamp 86 by means of bolts 92. The bracket 90 is resiliently connected to a complementary bracket 94 by means of an elastomeric mounting member 96. To this end a bolt 98 engaging the bracket 90 is embedded in the elastomeric element 96 at the top thereof. The bottom of the elastomeric element is welded to a metallic plate 102 secured to the bracket 94 by means of a bolt 100. Through this construction, the bracket 90 and its complementary bracket 94 are resiliently joined together such that the bracket 90 and the vibratory beam 68a supported thereby may vibrate independently of the bracket 94.

As best seen in FIGURE 7, the bracket 94 supports a pair of downwardly extending angle bars 104 which, in turn, support elastomeric bumpers 106. These bumpers 106 function to support the vibratory beam 68a against the drag of the concrete surface being finished.

The bracket 94 is supported in adjustable relation to the outer truss assembly 42 through the use of telescoping tubular members 108 and 110 best seen in FIGURE 6. The member 108 is welded at its lower end to the bracket 94 and slides into the member 110 which, as will be described subsequently, is fixedly secured with relation to the inner truss 54. The tubular members 108 and 110 are arranged vertically. A clamp, indicated generally by the reference numeral 112, engaging the lower end of the tubular member 110 is provided for locking the members 108 and 110 in fixed telescopic relation.

A bushing 114 provided in the top of the tubular member 110 rotatably receives a vertical screw lifting element 116 extending axially therein. The screw element 116 is retained at a fixed vertical elevation within the tubular member 110 by means of a collar 118 secured by a pin 120 and bearing against an annular ring 121 which, in turn, bears against the bushing 114. The extreme upper end of the screw element 116 is squared off at 122 for engagement by a suitable crank handle, not shown.

The screw element 116 engages an internally threaded portion 124 of the tubular member 108, such that upon rotation of the screw element 116, the tubular member 108 may be adjusted vertically upwards or downwards depending upon the direction of rotation of the screw element 116. The tubular member 110 is rigidly secured as follows.

A rectangular plate 126 is welded in face contacting relation to the outer wall of the tubular member 110. Bolts 128 secure the plate 126 to a transverse channel member 129 which, as appears in FIGURE 2, is an element of the inner truss assembly 54. Braces 130 and 132 welded to the plate 126 and the channel member 129, respectively, cooperate to reenforce the connection between these members.

In the foregoing, a vertically adjustable bracket assembly with which one end of the vibratory beam 68a is secured to the outer truss assembly 42 has been described. With reference to FIGURE 1, the extreme right end of the vibratory beam 68a is supported by a similar vertically adjustable lifting assembly identified generally with the reference numeral 136. The lifting assembly 136 is secured to a transverse channel member in the bottom of the outer truss assembly 42. Thus the vibratory beam 68a is supported at one end by the inner truss assembly 54, and at the other end by the outer truss assembly 42. Telescopic adjustment of the truss assemblies 42 and 54 is made permissible by a loosening of the hexagonal nuts 88 associated with the clamps 86 of the bracket assemblies supporting the vibratory beam 68a. This enables the clamps 86 to slide on the reinforcing rib 84 of the vibratory beam 68a.

In a similar manner the vibratory beam 68b, which is situated on the left end of the machine of FIGURE 1,

is supported by vertically adjustable lifting assemblies designated generally by the reference numerals 138 and 140. The lifting assembly 138 is secured to a transverse channel member 139, which as appears in FIGURE 2, is an element of the inner truss assembly 54. The lifting assembly 140 is secured to the transverse channel member 52b of the outer truss assembly 42.

The vibratory beam 68a is set into vibratory motion by means of a vibratory element 142, illustrated best in FIGURE 1. The element 142, which comprises a rotatably mounted shaft having an eccentric weight thereon, is of conventional construction and therefore not illustrated in detail. This vibratory element is clamped against the reinforcing rib 84 for the vibratory beam 68a. A motor 148 driving a belt 150 is utilized for operating the vibratory element.

As best illustrated in FIGURE 4, the motor 148 is mounted upon a plate 149. The plate 149 is supported above a parallel plate 146 by means of elastomeric spacer elements, not shown. The vibratory element 142 is clamped between the plate 146 and the reinforcing rib 84 by U-shaped brackets 144 penetrating the flange 80 and wrapping around the vibratory element 142 to engage the plate 146.

25 A duplicate vibratory assembly, designated in FIGURE 1 by the reference numeral 152, is employed for imparting vibration to the vibratory beam 68b. Electrical power is supplied to the assemblies for vibrating the beams 68a and 68b by means of an electrical generator 154 secured to the outer truss assembly 42 at the right end of the machine as illustrated in FIGURE 1. The delivery of electrical power to the vibratory assemblies is controlled by switches 156, illustrated to the right of FIGURE 1.

35 Due to the nature of the vibratory elements 142 used to impart vibration to the beams 68a and 68b, each of these beams is urged to vibrate in a circular pattern in a plane normal to the longitudinal axis thereof. The reinforcing ribs 84 associated with the vibratory beams 40 prevent longitudinal flexing of the vibratory beams thereby insuring that the beams vibrate uniformly in a circular pattern throughout their length.

The operation of the finishing machine is such as to draw the vibratory beams 68a and 68b over the surface of fresh concrete with the flanges 70 of the beams trailing the upright flanges 80 thereof. Due to the drag of the concrete on the trailing flange 70, the upright flange 80 is drawn against the adjacent bumpers 106. The bumpers 106 yield under the force created by drag on the flanges 70 until the elastic restoring forces therein counteract the drag force. These opposing forces bias the flanges 80 to an equilibrium vertical position. The bias is resilient or yieldable such that these flanges remain free to vibrate. Since the impressed vibration is rotary the flanges 80 will vibrate with a rotary movement.

60 The rotary vibratory movement of the flanges 80 is transmitted to the flanges 70. These flanges therefore also vibrate with a rotary motion. Thus, the flanges 70 will oscillate with a generally horizontal side to side motion and will simultaneously execute a vertical pivotal movement. Due to the vertical pivotal movement, the arcuate creases 82 between the flanges 70 and 80 of the beams 68a and 68b undergo repeated flexing such that the angle between the flanges 70 and 80 increases and decreases cyclically. It is to be observed that the creases 82 are in the form of a gentle curve as opposed to a sharp angular bend. This spreads the flexure of the metal in the creases over a wide area thereby reducing the susceptibility of the metal in the creases to work hardening and fatigue.

70 Preferably, the rest angle between the flanges 70 and 80 is about 93°. An angle in excess of 90° causes the flanges 70 to be inclined to the surface of the concrete deposit so that they will ski over the concrete surfaces.

The skiing action of the flanges 70 enables the vibratory deposit so that they will ski over the concrete surface with a minimum of distortion of the crown placed thereon.

In practice a condition of resonance develops between the vibratory movement of the beams 68a and 68b and the impressed vibratory frequency. The condition of resonance is particularly noticeable in the flanges 70 which vibrate with a much greater amplitude than that found in the movement of the vibratory element 142.

The large amplitude vertical vibration of the flanges 70 produces a slapping or whipping action such that the surface of the concrete deposit 62 is repeatedly struck with great force. This induces vibration in the concrete body as illustrated schematically in FIGURE 4. Preferably, the impressed vibratory frequency is in the range of 70-90 cycles per second.

The vibrations induced in the concrete body are duofunctional. First, they compact the freshly laid concrete eliminating any voids therein. Second, a layer of grout is brought to the surface of the concrete deposit to enable final finishing to be done quickly.

The construction of the strike-off bar 64 and the supporting structure therefor will now be described. As appears in FIGURE 1, the strike-off bar 64 is formed of a number of segments identified by the numbers 170a, 170b, 170c, 170d, 170e and 170f. The extreme left end of the strike-off bar 64, as viewed in FIGURE 1, connects to a pair of baffles numbered 172a and 172b. The baffle 172b serves as a scraper for the left rail on which the machine rides. Similar baffles are provided at the opposite or right end of the strike-off bar.

The segment 170a of the strike-off bar is illustrated in detail in FIGURES 8 and 9. Referring to FIGURE 8, which shows the segment 170a in end elevation, it is seen that this segment comprises a unitary sheet folded so as to have substantially right angularly disposed flanges 174 and 178. The flange 174, which is oriented vertically, has its lower margin struck outwardly to form a scoop or inclined plane 176. The segments 170b, 170c, 170d, 170e, and 170f are similarly formed and, as appears in FIGURE 1, the inclined planes 176 in each segment align to form a continuous inclined plane surface for scraping or planing the surface of the concrete deposit over which the machine is moved.

Referring to FIGURES 8 and 9, the segment 170a of the strike-off bar is reinforced by right angular rib elements 180 and 182 formed from lengths of angle bar welded together. These rib elements are welded in place on the segment 170a. Other reinforcement, not illustrated, may be provided as required.

The structure for supporting the segment 170a with respect to the finishing machine includes a hinge element 184 welded to the reinforcing rib elements 180 and 182. This hinge element is pivotally engaged by a vertically disposed tubular member 186 provided at its lower end with a clevis 188. The tubular member 186 fits telescopically into a larger tubular member 190 and is threadedly engaged by a vertical screw lifting element 192. The assembly of telescopic tubular members 186 and 190 is substantially identical in construction to the assembly of telescopic tubular members 108 and 110 illustrated in FIGURE 6 and described hereinbefore.

The tubular member 190 is connected to a channel member 198 which is part of the outer truss assembly 48. To effect this connection a plate 194 is welded in face contacting relation to the tubular member 190 and bolted to the channel member 198 with bolts 196. A brace 200 welded to the plate 194 and a brace 202 welded to the channel member 198 cooperate to strengthen the connection between the channel member 198 and the tubular member 190.

It is evident from the foregoing construction that rotation of the screw lifting element 192 may be employed to raise and lower the segment 170a of the strike-off bar

5 64. In a similar manner, the segment 170b is connected by means of an adjustable assembly of telescopic tubular lifting members designated generally by the reference numeral 210 to a transverse channel member 211 of the outer truss assembly 48. The segment 170c, which is substantially at the center of the strike-off bar 64, is secured by means of an adjustable assembly of telescoping tubular lifting members designated by the reference numeral 212 to the transverse channel member 129 of the inner truss assembly 54. The segment 170e is secured to the transverse channel member 46a of the outer truss assembly 42 by means of an assembly of telescoping tubular lifting members designated by the reference numeral 214. The assembly 214 is shown in fragmentary detail. The segment 170f of the strike-off bar 64 is secured by means of an adjustable assembly of telescoping tubular lifting members designated generally by the reference numeral 216 to a transverse channel member 218 of the outer truss assembly 42.

20 Adjacent pairs of the segments 170a-f are joined in the manner illustrated in FIGURE 10. Specifically, this figure shows the connection between the segments 170e and 170f. To effect the connection, the segment 170e is provided at its end with a right angular reinforcing rib 220 formed of angle bar stock. A short distance inwardly of its end, the segment 170f is provided with a similar right angular reinforcing rib 222. When the segments 170e and 170f are butted together in end-to-end relation, the reinforcing ribs 220 and 222 are distributed in parallel relation with a small gap therebetween. The reinforcing rib 220 is so positioned on the segment 170e that it overlaps the seam between the segments 170e and 170f.

25 The reinforcing ribs 220 and 222 are bolted together at their opposite ends by means of bolts 224 and 226. A bearing 228 is positioned between these two reinforcing ribs in the corners thereof. The bearing 228 is secured between the ribs by means of a bolt assembly, not illustrated, the bolt of this assembly passing through the upright flanges of each of the ribs 220 and 222 and through the center of the bearing 228.

30 The opposite ends of the bearing 228 are tapered so as to reduce the area of contact between the ends of the bearing 228 and the reinforcing ribs 220 and 222. By virtue of this reduced area of contact, the segments 170e and 170f are permitted limited pivotal movement on the bearing 228 whenever the bolts 224 and 226 connecting the ends of the reinforcing ribs 220 and 222 are loosened. This type of connection enables the segments 170e and 170f to be adjusted to a desired angular relationship with the bolts 224 and 226 loosened, then to be fixed at that angular relationship by tightening the bolts 224 and 226.

35 A similar connection is provided between all adjacent segments of the strike-off bar. At those junctions where the segments are supported by an adjustable lifting support, such as the junction between the segments 170d and 170e, the upper bolt 224 is replaced by an unthreaded shaft. As a result these adjacent segments are, at all times, free to pivot with adjustment of the lifting support. The arrangement is such that by loosening the connecting bolts between all of the segments of the strike-off bar and by thereafter adjusting the elevation of the strike-off bar by means of the adjustable lifting supports for the segments 170a, 170b, 170c, 170e and 170f, the strike-off bar may be formed to a desired curvature in the vertical plane. Once the desired curvature has been established, it may be fixed by tightening the bolts joining the ends of adjacent segments. With this type of assembly, the strike-off bar 64 may be adjusted within reasonable limits to place any desired crown on the concrete surface which is to be finished.

40 The adjustable lifting supports for the strike-off bar 64 have a secondary function. It is not possible as a practical matter to preserve the adjustment of the finish-

ing machine indefinitely. The adjustable lifting supports permit adjustment to correct small errors in the alignment of the strike-off bar as they develop.

The operation of the finishing machine will now be described. With the finishing machine situated upon rails 10 over the surface which is to receive a concrete finish, the strike-off bar 64 is adjusted to provide the desired crown in the concrete surface by adjusting the various adjustable telescoping lifting assemblies 190, 210, 212, 214 and 216. The bolts connecting the ends of the strike-off bar segments, which are loosened to permit the initial adjustment of the strike-off bar, are thereafter tightened to fix the curvature of the strike-off bar. The strike-off bar is then adjusted to the desired elevation relative to the ground through adjustment of the pins 40 in the holes 38 of the brackets 22 at the opposite ends of the finishing machine. This latter adjustment is accomplished without altering the crown setting. Usually, the strike-off bar is set $\frac{1}{2}$ inch or so above the desired surface elevation to allow for subsequent compaction.

The vibratory beams 68a and 68b are adjusted to accommodate the crown of the concrete surface. This adjustment is effected by adjustment of the telescoping lifting assemblies 116, 136, 138, and 140. FIGURE 5 illustrates the manner in which the vibratory beams 68a and 68b are adjusted to accommodate the crown of the concrete surface. In this figure the shape of the crown is illustrated schematically by the broken arcuate line 240. The vibratory beams 68a and 68b, which are always maintained in overlapping end-to-end relation, are adjusted so that the point at which their flanges 70 cross is at the top of the crown when the opposite ends of the beams 68a and 68b also lie on the surface of the crown. Preferably, the aforementioned points are set about $\frac{1}{4}$ inch below the ultimate crown surface. This insures effective action of the vibratory beams throughout the entire width of the concrete surface being formed. The arcuate crease 82 in each vibratory beam functions to guide the upper portions of the concrete surface under the flange 70.

Following the adjustments outlined in the foregoing, the generator 154 is put into operation so that the vibratory beams 68a and 68b are continuously vibrated. As concrete is poured forward of the machine, the machine is advanced at a uniform rate to finish the concrete. Preferably, the elevation of the concrete placed in front of the machine is such that a roll of approximate 2 inches height will be maintained in front of the strike-off bar at all times.

It has been found that this concrete finishing machine will operate continuously for long periods of time without attention. At any time, as for example when it may be desired to make small adjustments on the machine or to discontinue the operation of the machine, both the strike-off bar 64 and the vibratory beams 68a and 68b may be picked up off the concrete surface by movement of the lever arms 28 at the opposite ends of the finishing machine in the counterclockwise direction as viewed in FIGURE 1.

As described hereinbefore, the overall length of the concrete finishing machine is variable due to the use of telescoping truss assemblies. The overall length of the strike-off bar 64 is adjustable by adding or removing segments, like the segment 170d, which are of varying length. These segments may be added on either side of the segment 170c. Ordinarily, a sufficient number of extra segments is kept on hand so that the strike-off bar 64 may be adjusted to any of the standard road widths between the maximum and minimum widths to which the present concrete finishing machine may be adjusted.

The vibratory beams 68a and 68b each have a length slightly exceeding one-half the maximum length of the finishing machine. As a result, even when the machine is adjusted to its maximum width, there will be a partial overlap between the ends of the vibratory beams 68a and

68b. As noted hereinbefore, the clamping assemblies 86, engaging the overlapping ends of the vibratory beams, must be loosened so that they may slide upon the reinforcing ribs 84 whenever the overall length of the concrete finishing machine is changed.

5 Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. An apparatus for finishing the surface of fresh concrete comprising a vibratory beam, structure for supporting said beam upon the concrete surface, said beam comprising a pair of elongate substantially planar flanges, one of said flanges adapted to be normal to the concrete surface and the other of said flanges adapted to be substantially parallel to and in contact with said concrete surface, there being a margin of said one flange in proximate relation to a margin of said other flange, a flexible arcuate portion uniting said proximate margins whereby said beam has a substantially L-shaped section, said structure including means engaging said one flange and resiliently supporting said beam from said structure for vibratory movement relative to said structure, a vibrating unit for transmitting vibratory motion to said one flange, said arcuate portion having a flexibility sufficient to permit resonant vibration of said other flange about a longitudinal axis defined by said flexible portion at the frequency of the impressed vibratory motion, said flanges being sufficiently similar in width to accomplish such vibration, and reinforcing means engaging said beam and extending longitudinally along the length thereof to prevent resonant transverse vibration of said beam except at frequencies higher than that of the impressed vibration.

2. An apparatus for finishing the surface of fresh concrete including a vibratory beam, said beam comprising an elongate flexible metallic sheet provided with a longitudinal arcuate crease forming two angularly disposed flanges thereof, one of said flanges being vertical and the other substantially horizontal, means providing a reinforcing rib along the free margin of the vertical flange, and vibratory means engaging said reinforcing rib for imparting vibration to said beam, said means vibrating normal to the longitudinal axis of said beam, said reinforcing rib imparting sufficient rigidity to said beam to prevent resonant transverse vibration of said beam except at frequencies higher than that impressed by said vibratory means, and said arcuate crease having sufficient flexibility to permit resonant vibration of said horizontal flange about a longitudinal axis defined by said crease at the frequency of vibration impressed by said vibratory means, said flanges being sufficiently similar in width to accomplish such vibration.

3. The apparatus according to claim 2, wherein said substantially horizontal flange is disposed in trailing relation to said vertical flange at an angle thereto exceeding 90° , the arcuate crease therebetween functioning to guide upwardly projecting portions of said concrete surface under said substantially horizontal flange.

4. In an apparatus for finishing the surface of a fresh concrete deposit, an elongate beam, structure for supporting said beam parallel to the surface of said deposit, and means for vibrating said beam, the improvement wherein said beam comprises an elongate strip of flexible metallic material having an arcuate longitudinal crease therein forming two angularly disposed flanges thereof, and means providing an elongate reinforcing rib along the free margin of one of said flanges, said structure including resilient mounting means engaging said reinforcing rib to support said beam for independent vibratory mo-

tion, said one flange adapted to be oriented substantially normal to the plane of said concrete surface and supporting said vibratory means, the other flange having one face adapted to contact said concrete surface, said reinforcing rib imparting sufficient rigidity to said beam to prevent resonant transverse vibration of said beam except at frequencies higher than that impressed by said vibratory means, and said arcuate crease having sufficient flexibility to permit resonant vibration of said other flange about a longitudinal axis defined by said crease at the frequency of vibration impressed by said vibratory means, said flanges being sufficiently similar in width to accomplish such vibration.

5. An apparatus for finishing the surface of a fresh concrete deposit including a vibratory beam, structure for supporting said beam upon said deposit, said beam including a pair of elongate flanges of flexible material arranged at an angle and united by an arcuate flexible portion so as to have a substantially L-shaped section, and means providing an elongate reinforcing rib along the free margin of one of said flanges, vibratory means engaging said rib to vibrate said beam, said structure including a supporting bracket, a complementary bracket engaging said reinforcing rib, and an elastomeric body joined to both said brackets providing a resilient connection therebetween, said brackets supporting the reinforced flange of said beam substantially normal to the surface of said concrete deposit, the other flange of said beam adapted to be disposed in face contacting relation to said concrete deposit, said reinforcing rib imparting sufficient rigidity to said beam to prevent resonant transverse vibration of said beam except at frequencies higher than that impressed by said vibratory means, and said arcuate flexible portion having sufficient flexibility to permit resonant vibration of said other

flange about a longitudinal axis defined by said flexible portion at the frequency of vibration impressed by said vibratory means, said flanges being sufficiently similar in width to accomplish such vibration.
